Inventor
Louie Stern
By his Attorney
Aaron B. Siscarud

UNITED STATES PATENT OFFICE.

LOUIE STERN, OF NEW YORK, N. Y.

LOCK.

1,215,888.

Specification of Letters Patent. Patented Feb. 13, 1917.

Application filed October 21, 1916. Serial No. 126,848.

To all whom it may concern:

Be it known that I, LOUIE STERN, a citizen of the United States, and a resident of New York city, in the county and State of New York, have invented certain new and useful Improvements in Locks, of which the following is a specification.

This invention relates to a lock of novel construction which is more particularly adapted for doors, though it may also be used for other devices.

Briefly stated, the invention comprises a lock having a pair of axially alined upright bolts that may be moved simultaneously in opposite directions and are adapted to engage opposite sides of a keeper. The invention further comprises means for locking the bolts against movement, common means for operating a latch either alone or in conjunction with the bolts, and various other features of novelty more fully pointed out in the specification and appended claims.

In the accompanying drawings:

Figure 1, is a longitudinal section of a lock embodying my invention on line 1—1 Fig. 2;

Fig. 2, a face view partly in section with the lock plate removed;

Fig. 3, a similar view showing the parts 30 in a different position;

Fig. 4, a cross section on line 4—4 Fig. 1;

Fig. 5, a cross section on line 5—5 Fig. 2;

Fig. 6, a perspective view of the two bolts;

Fig. 7, a perspective view of the forked lever and coöperating catch and

Fig. 8, a rear view of the catch.

The lock case 1 is adapted to be secured by screws 2 to the inner side of a door or similar

device 3. Case 1 is furnished at the end facing the jamb 4, with upper and lower extensions 5, adapted to straddle the keeper

6, which is attached to jamb 4 by screw 7. Extensions 5, are provided with axially

aligned bores, which with door locks are arranged vertically one above the other. These bores accommodate a pair of opposed or axially alined bolts 8, that are adapted to be simultaneously moved inward or into engagement with the keeper, or outward so as

to clear the latter and become housed within extensions 5. Bolts 8, are by cross pieces 9 connected to a pair of shanks 10, in such a

manner that each bolt is arranged in substantial parallelism with its shank and that

the bolts project inwardly from the cross pieces and face each other with their free or operative ends (Fig. 6). Within casing 1, there is provided, a fixed rail or projection 11 that spaces shanks 10, and forms a guide 60 therebetween along which said shanks are slideable simultaneously in opposite directions. To rail 11 there is pivoted at 12, a lever or oscillable member 13, having a pair of pins 14, that engage elongated slots 15 65 of shanks 10. Lever 13 is provided at one end with a forked head 16, which is undercut or slotted sidewise as at 17 (Fig. 7). Head 16, is adapted to be operatively engaged by either one of a pair of pins 18, 70 mounted on opposite ends of an arm or rotatable member 19, fast on the spindle 20, of the manually operable knob 21 that projects from the inner side of the door. Pins 18 are also adapted to engage the arched cross bar 75 22 of a yoke comprising a pair of axially slideable shafts 23, to which a plate 24 carrying the latch tongue 25 is secured, such tongue being centered between bolts 8 and movable at right angles thereto. Shafts 23, 80 are encompassed by springs 26, abutting at one of their ends against fixed stops 27 of lock case 1, said springs having a tendency to advance the latch and thus draw cross bar 22 into operative engagement with pins 85 18, during all positions of arm 19.

To a post 28, of lock case 1, is pivoted a hook-shaped catch 29 adapted to enter slot 17 and by grasping fork 16, lock lever 13 and consequently hold shanks 10 against movement. Catch 29 is provided with a shoulder 90 30, engaged by a cam edge 31 formed on one of the shanks 10, and against which the catch is drawn by a spring 32.

At the outer side of the door, there is provided, the usual key operated barrel 33 having a blade 34, that projects into a slotted stud 35, rotatably fitted in the lock plate 36. This stud carries an arm 37 which is a substantial counterpart of arm 19, but has a 100 single pin 38 only in lieu of the two pins 18 carried by arm 19.

Keeper 6, is provided with a vertical bore 39 adapted to receive at its opposite ends, bolts 8, and with an intermediate slot 40 105 adapted to receive latch 25.

If the bolts are retracted and it is desired to operate the latch alone, arm 19 is by knob 21, turned in either direction, to such an extent only, that cross bar 22 is by either one 110

of the pins 18, drawn inward to an extent sufficient to retract latch 25 against action of springs 26.

If it is desired to shoot bolts 8, arm 19 is by knob 21 turned to such an extent that one of its pins 18, will enter forked head 16, and swing lever 13 on its pivot 12 into its terminal position, (Fig. 2). The further rotation of the knob will serve to withdraw the active pin 18 out of forked head 16 and to engage cross bar 22, so as to retract latch 25 in manner previously described. As lever 13 is being turned it will by pins 14, slide shanks 10 in opposite directions toward each other, so as to impart a corresponding movement to bolts 8, and cause the latter to enter bores 39 of keeper 6 from opposite sides. During this sliding movement of shanks 10, the receding section of cam 31 will be gradually brought into engagement with shoulder 30, so that catch 29 will, by its spring 32, be thrown up through slot 17, into engagement with forked head 16 and thus lock the bolts against movement.

When it is desired to retract the bolts, arm 19 is by knob 21 turned in the opposite direction whereby pin 18, will reenter head 16, and during the first part of its movement, push catch 29 (which had projected a distance into the head) out of the fork. The further turning of knob 21, will cause lever 13 by its pins 14, to slide shanks 10 in opposite directions away from each other, so as to impart a corresponding movement to bolts 8, and cause the latter to clear the bores 39 of keeper 6.

During this sliding movement of shanks 10, the salient section of cam 31 will be gradually brought into engagement with shoulder 30, so that catch 29 will, against the action of its spring 32, be retracted or swung down (Fig. 1).

As the turning of knob 21 is continued, pin 18 will leave forked head 16, and by engaging cross bar 22, will operate the latch.

When the lock is operated from the outside by means of a key, the operation is the same as above described. However, a single pin 38 on the operating arm 37, will now suffice, for the reason that the latter must always be given such an extensive turn as will operate lever 13 and thus either advance or retract the bolts.

It will be seen that a lock constructed as described, cannot be opened by forcing the door or door jamb, for the reason that as the

bolts project into the keeper from opposite directions, such forcing cannot release the lock from the keeper. So also the knob or the key serves to not only operate the latch 60 but also the latch conjointly with the bolts, whereby simplicity in manipulation is effected.

Finally, the lock is of simple construction and may be readily assembled, inspected or repaired.

I claim:

1. A lock comprising a case, a pair of enclosed parallel axially slidable shanks, a pair of inwardly directed bolts carried by the shanks and arranged in parallelism therewith, means for simultaneously sliding said shanks in opposite directions and an apertured keeper adapted to be straddled by the case and to be engaged by the bolts. 70

2. A lock comprising a case, a pair of enclosed parallel axially slidable shanks, a pair of inwardly directed bolts carried by the shanks and arranged in parallelism therewith, a lever engaging the shanks, a pivoted arm adapted to operatively engage said lever, and an apertured keeper adapted to be straddled by the case and to be engaged by the bolts. 80

3. A lock comprising a case, a pair of enclosed parallel axially slidable shanks, a pair of inwardly directed bolts carried by the shanks and arranged in parallelism therewith, a lever engaging the shanks, a pivoted arm adapted to operatively engage 90 said lever, a yoke engaging said arm, a latch carried by the yoke, and an apertured keeper adapted to be straddled by the case and to be engaged by the bolts. 85

4. A lock comprising a case, a pair of opposed bolts having slideable shanks and inwardly directed free ends, a forked lever operatively connected to said shanks, a pivoted arm having a pin adapted to engage said lever, a yoke engaging said arm, and a latch carried by the yoke. 95

5. A lock comprising a case, a pair of opposed bolts having slideable shanks, a forked lever operatively connected to said shanks, a catch adapted to lock the forked lever, a cam 105 on one of the bolt-shanks adapted to engage the catch, a pivoted arm adapted to engage the forked lever, a yoke that is engaged by the pivoted arm, and a latch carried by the yoke.

LOUIE STERN
